AGITATOR

Louis Solomon, Jamaica, N. Y.

Application August 22, 1947, Serial No. 770,145

3 Claims. (Cl. 259—108)

1

The present invention relates to an improvement in agitating devices such as are employed in conjunction with drums or similar containers which are used in the handling of paint and similar materials and in which the need for stirring or mixing the contents of the drum is necessary.

Normally in the use of agitating devices, the bunghole cap is removed and a stirring handle is operatively connected to the top of the stirrer which extends part way out of the bunghole for this purpose. It is essential that the upper end of the stirrer be maintained in a positive manner in the bunghole at all times so that there is no possibility of the stirrer being displaced from the bunghole and of dropping into the interior of the paint drum. Even during the interval of time necessary to connect or disconnect the handle to the stirrer it is desirable that the upper end thereof be positively maintained against any such displacement.

It is an object of this invention to provide means whereby the upper end of the stirrer is positively maintained against displacement from a position within the bunghole at all times during the use of the drum including not only the time when the bunghole is closed but also the time when the bunghole is opened and the upper end of the stirrer is raised to connect or to disconnect the stirring handle. If during the operation of connecting or disconnecting the stirring handle, the stirrer blade should slip from the hand of the operator as it may well do because of the paint, by means of the improvement of the present invention the stirrer blade will still be maintained within the bunghole and will not slip down into the drum.

These and other objects of the invention will be apparent from the following description thereof taken in connection with the accompanying drawings in which:

Figure 1 is a vertical cross section of a drum showing the agitator in place therein;

Figure 2 is a cross sectional view of the bunghole assembly in the top of the drum;

Figure 3 is a cross sectional view showing the relation between the bunghole cap and the upper end of the stirrer blade;

Figure 4 is a bottom view of the parts shown in Figure 3, as taken along the line 4—4 of Figure 3;

Figure 5 is a plan view of a portion of the top of a drum showing the open bunghole and a modified form of supporting means for the agitator blade;

2

Figure 6 is a cross sectional view of Figure 5 taken on line 6—6 thereof showing the bunghole cap in place; and

Figure 7 is a cross sectional view of the bunghole and a portion of the top of a drum with the stirring handle connected to the agitator blade.

In the drawings a drum is shown at 10 having the stirrer or agitator blade 11 which is adapted to be rotated in the usual manner by means of a handle 12 which is inserted within a hole 13 formed in the upper end of the stirrer, as is most clearly shown in Figure 7.

In the top 14 of the drum 10 there is provided a hole within which an internally threaded bunghole fitting of the type shown at 15 in Figure 2 or of the type shown at 16 in Figure 6 is secured in place. It will be noted that each of the bunghole fittings 15 and 16 have a top flat surface 17 and when the externally threaded bunghole cap 18 is screwed in place in the bunghole fittings, a washer 19 acts as a seal between the surface 17 and the undersurface 20 of the cap 18 entirely surrounding the threaded hollow plug portion 18a of the same, thus forming an air tight joint. It will be noted that a slot 21 has been cut diametrically through the annular wall of the threaded plug portion 18a of the cap 18, for a purpose to be described, but this slot is cut only to and not beyond the under surface 20 so that the surfaces 17 and 20 with the washer 19 therebetween can form an air tight joint for the drum.

The edge of the opening in each of the bunghole fittings 15 and 16 is preferably rounded, as at 22, to provide an annular seat for a supporting member 23 secured to the upper end of the stirrer blade 11. The member 23 preferably consists of a transversely extending metal bar slotted as at 24 to receive therein the upper end of the stirrer blade 11, the blade being retained in the slot 24 by means of a rivet 25 or the like. Each opposite end of the bar 23 is undercut as at 26, 26, the bar being of such length that while the undercut portions 26, 26 fit within the bunghole fittings, the ends of the bar rest upon the rounded edge surfaces 22 of the openings in the fittings and prevent the bar 23 from passing therethrough. Accordingly it will be apparent that the bar 23 fastened transversely across the top of the stirrer blade 11 effectively serves as a support for the blade to prevent the same from passing through the bunghole fittings 15 or 16.

The slots 21 in the bunghole cap 18 embrace the supporting bar 23 in such manner that the cap may be readily threaded into the bunghole 55 fitting with the bar 23 extending transversely

thereof. Since the ends of the supporting bar 23 resting on the rounded edges 22 of the bunghole fitting do not extend beyond the washer 19, the bar 23 does not interfere with the sealing action of the cap 18 when it is screwed into place. It will be noted with respect to the arrangement illustrated in Figures 1 to 3 that since the bar 23, is embraced by the diametrically opposed slots 21 of the cap, the bar 23 and the associated stirrer blade 11 will turn with the cap 18 when the latter is threaded into the bunghole fitting.

In Figures 5, 6 and 7 there is shown a modified arrangement in which the supporting bar 27 is centrally apertured, as at 28, for projection therethrough of a beaded pin 29 which is fixedly secured to or formed as an integral element of the stirrer blade, the bar 27 being thus rotatably secured to the upper end of the stirrer blade 11. In this modified construction it will be noted that while the bar 27, being disposed within the slots 21, will turn with the cap 18, the bar 27 will be free to rotate relatively to the stirrer blade 11, in consequence of which the latter may remain stationary within the drum as the closure cap 18 is threaded into or out of the bunghole fitting.

In the use of the device herein described the transversely extending supporting bar 23 (of Figures 1 to 3) or 27 (of Figures 5 to 7), being of greater length than the diameter of the bunghole opening, prevents the stirrer blade from dropping downwardly into the drum. By virtue of the fact that the ends of the supporting bar are nested within the diametrically opposed slots 21-21 formed in the closure cap 18, the supporting bar does not interfere with the closing of the drum nor with the proper sealing thereof. When the cap is removed and it is desired to insert the arm 12 in the opening 13 in the stirrer blade, the supporting bar of either form shown and described, remains in place and does not interfere with the usual lifting of the stirrer blade sufficiently for this purpose and if by chance the stirrer blade should slip out of the hand of the operator, the supporting bar immediately assumes a position extending transversely of the bunghole fitting to prevent the stirrer blade from dropping into the drum.

It will be understood, of course, that the present invention is susceptible of various other changes and modifications which may be made from time to time without departing from the general principles or real spirit thereof, and it is accordingly intended to claim the same broadly as well as specifically as indicated in the appended claims.

What is claimed as new and useful is:

1. A container having an internally threaded bunghole fitting therein, an externally threaded closure cap therefor having a slot extending diametrically across the threaded portion thereof and a stirring blade adapted to be disposed with the upper end thereof within the opening of said fitting, and supporting means for said blade non-removably secured to the upper end thereof in the form of a transversely extending bar having undercut ends adapted to engage the peripheral upper edge of said fitting to prevent said blade from dropping into said container, said supporting bar being disposed within said bunghole with the upper edge thereof substantially flush with the upper edge of said fitting and with its intermediate body portion adapted to fit within the slot in said cap.

2. A container as set forth in claim 1 in which said supporting bar, said blade and said cap move in unison relative to said fitting as said cap is turned relatively to said fitting.

3. A container as set forth in claim 1 in which said supporting bar is rotatably secured to said blade so that said bar and said cap move in unison relative to said fitting and relative to said blade.

LOUIS SOLOMON.
